[57] CLAIM

The ornamental design for a padlock cover with storage compartment, as shown and described.

DESCRIPTION

FIG. 1 is a bottom, front, and right side perspective view of a padlock cover with storage compartment showing my new design, the broken-line depiction of a padlock throughout the views being for illustrative purposes only and forming no part of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 1.

FIG. 4.

FIG. 2.

FIG. 3.

FIG. 5.

FIG. 6.

FIG. 7.
